(57) **CLAIM**

I claim the ornamental design for a loader, as shown and described.

DESCRIPTION

FIG. 1 is a perspective view of a first embodiment of a loader.

FIG. 2 is a right elevation view of the loader shown in FIG. 1.

FIG. 3 is a left elevation view of the loader shown in FIG. 1.

FIG. 4 is a front elevation view of the loader shown in FIG. 1.

FIG. 5 is a rear elevation view of the loader shown in FIG. 1.

FIG. 6 is a top plan view of the loader shown in FIG. 1.

FIG. 7 is a bottom plan view of the loader shown in FIG. 1.

FIG. 8 is a perspective view of a second embodiment of a loader.

FIG. 9 is a right elevation view of the loader shown in FIG. 8.

FIG. 10 is a left elevation view of the loader shown in FIG. 8.

FIG. 11 is a front elevation view of the loader shown in FIG. 8.

FIG. 12 is a rear elevation view of the loader shown in FIG. 8.

FIG. 13 is a top plan view of the loader shown in FIG. 8.

FIG. 14 is a bottom plan view of the loader shown in FIG. 8.

FIG. 15 is a perspective view of a third embodiment of a loader.

FIG. 16 is a right elevation view of the loader shown in FIG. 15.

FIG. 17 is a left elevation view of the loader shown in FIG. 15.

FIG. 18 is a front elevation view of the loader shown in FIG. 15.

(Continued)

FIG. 19 is a rear elevation view of the loader shown in FIG. 15.

FIG. 20 is a top plan view of the loader shown in FIG. 15; and,

FIG. 21 is a bottom plan view of the loader shown in FIG. 15.

The evenly-spaced broken lines illustrate portions of the loader that form no part of the claimed design; the dash-dot-dash broken lines represent the bounds of the claimed design and form no part thereof.
